[57] CLAIM

The ornamental design for a freestanding display rack
for rolled material, substantially as shown and de-
scribed.

DESCRIPTION

FIG. 1 is a perspective view of a freestanding display
rack for rolled material showing my new design;

FIG. 2 is a front elevational view thereof;

FIG. 3 is a top plan view thereof;

FIG. 4 is a right side elevational view, the left side being
a mirror image thereof; and

FIG. 5 is an end view similar to that of FIG. 4, but with
its upper portion rotated to a position transverse to its
lower portion.

The broken lines in the drawings show rolls of sheet
material displayed on the freestanding display rack for
rolled material for purposes of illustration only.
